EXPANSIBLE BUILDING STRUCTURE

Archie B. Gray, Shannon City, Iowa

Application January 21, 1937, Serial No. 121,533

9 Claims. (Cl. 20—2)

The object of my invention is to provide a building structure relatively long and narrow, such, for instance, as an automobile trailer, which may be readily, quickly and easily expanded to 5 approximately twice its original width, and again contracted.

More specifically, it is my object to provide a structure of this class in which, upon the manual operation of a shaft on the foundation frame, the 10 side walls, the end walls and the roof will be simultaneously moved to their expanded positions, and in the same manner returned to their contracted positions.

A further object is to provide a structure of 13 this class in which all of the joints between the various elements of the structure will automatically assume substantially weather tight positions when fully expanded or fully contracted.

A further object is to provide a structure of 20 this class in which all of the various elements of the structure will be automatically held in position against adjacent structural elements, under tension, either when fully expanded or fully contracted, to thereby avoid rattling and friction.

25 A further object is to provide simple, durable and inexpensive means for moving the floor section from fully extended to fully contracted positions and back, and to securely hold the folding floor sections under tension when in its contracted position.

30 A further object is to provide an improved folding floor for the extensible sides of the trailer which, when in folded position, will extend upwardly adjacent the side wall only a short distance so that when in folded position it will not interfere with the furniture, plumbing, cabinets, etc., usually fixed to the side wall a short distance above the floor, and further to provide means for 35 moving the folding floor sections quickly and easily from one position to the other by the same operation as is used to extend and contract the side walls, thereby adding to the ease and convenience of the operator in moving the entire structure from collapsed to extended position and back.

35 In the accompanying drawings Figure 1 shows a side elevation of my improved building structure in its fully collapsed position.

40 Figure 2 shows a similar view in its fully expanded position.

45 Figure 3 shows an end elevation of same with one of the upright side walls and associated members in a fully extended position and the other 50 side wall and associated members in fully con-

tracted position. The dotted lines show this latter side wall in its fully extended position.

55 Figure 4 shows a detail sectional view of a portion of the roof illustrating the manner in which the hinged roof section is made to assume a weather tight condition when expanded.

Figure 5 shows a central transverse vertical sectional view of my improved building structure in its fully collapsed position.

Figure 6 shows an enlarged detail vertical sectional view on the line 6—6 of Figure 5.

Figure 7 shows an enlarged detail horizontal sectional view showing one corner of the structure just above the floor.

Figure 8 shows an enlarged detail sectional view on the line 8—8 of Figure 3.

Figure 9 shows a detail horizontal sectional view of a modification showing a portion of the main floor, a portion of the folding floor and the mechanism for folding and unfolding the folding floor.

Figure 10 shows a detail vertical sectional view of same taken on the line 10—10 of Figure 9; and

Figure 11 shows a vertical sectional view of the same parts shown in Figure 9; the dotted lines 25 show the folded positions of the floor and adjacent side wall.

My improved building structure comprises a foundation frame indicated generally by the reference numeral 10, and preferably made of 30 structural steel. This frame is of the maximum length of the structure, but its width is that of the structure when fully collapsed, such, for instance, as may be used as an automobile trailer. At each end of the foundation frame there is an 35 upright end wall member 11 which is also of the minimum width of the structure. One or both of these end walls has formed therein a door opening, as indicated at 12 in Figure 5, and a door 13 for said opening, and the two end walls support the 40 main roof section 14. All of said foundation frame, end walls and roof are preferably supported by structural steel frame members.

Each of the end wall members has associated with it two upright extension end wall members 45 15. These extension end wall members are slidably mounted in grooved supports 16, shown in Figures 2 and 3, which grooved supports extend inwardly only to the door opening 12, as shown in Figure 3.

The inner upright portions of these extension end wall members are provided with hinged sections 17 hinged to the sections 15, as shown in Figure 3. When these extension end wall members are in their fully collapsed position, as shown 55

at the right in Figure 3, the door section 17 may be opened. When, however, they are in their fully extended position, as shown at the left in Figure 3, the door section 17 is held against opening movement because it is held in the grooved support 16.

The side walls are indicated generally by the reference numeral 18. These side walls have at their lower edges a series of channel bars 19, as shown in Figure 6, extending horizontally across the foundation frame and then upwardly, and the foundation frame is provided with a channel bar 20 in which the channel bars 19 are slidingly mounted; preferably the inner ends of the channel bars 19 are provided with rollers 21 to engage the channel bar 20 to avoid friction, while the outer ends of said channel bars are supported by rollers 21a secured to the frame member 10. The channel bars 20 extend from the side walls inwardly to a point adjacent the opposite side of the foundation frame.

Said extension end wall members 15 are fixed at their outer edges to the adjacent side wall member 18, as shown in Figure 7, so that as the side wall members are moved outwardly and inwardly, these end wall members 15 will be correspondingly moved. For the purpose of limiting the outward movement of the side and extension end wall members I have provided on the foundation frame an upright angle bar 22 at the corner of the foundation frame, one flange of which extends inwardly toward the longitudinal center of the structure, and on the inner end of the end wall member 15 I have formed a sealing hook 23 extending up and down the full length of the end wall member, and these parts are so shaped that, when the side wall and the end wall member 15 are moved outwardly from the position shown in Figure 7, this sealing hook 23 will engage and receive the adjacent flange of the angle bar 22 and thereby limit the outward movement of the side wall and at the same time form a weather tight seal at this point.

The inward limit of movement of the side wall members is determined by the engagement thereof with the adjacent portions of the end walls when in fully collapsed position.

Mounted on top of the foundation frame is a central or stationary floor section 24, being approximately the width of the complete structure when fully collapsed. At each side edge thereof there is a folding floor section 25 hinged to the main floor section, and capable of swinging from a vertical position, as shown in Figure 5, to a horizontal position. When these floor sections 25 are in upright position, as shown in Figure 5, they engage the frame members 26 on the end wall members, as shown in Figure 5, to thereby limit their inward movement, and these upright frame members 26 also support the pulleys 27 hereinafter described.

For the purpose of raising and lowering these hinged floor members I have provided a shaft 28 mounted in the foundation frame and extended longitudinally thereof near the center. This shaft has a pulley 29 fixed to it, and a flexible cable 30 is attached at one end to, and is wound upon, the pulley 29, and its other end is extended upwardly over the pulley 27 and attached to the adjacent floor section 25. On one end of this shaft 28 is a notched wheel 32, and a pawl 33 is pivoted adjacent to the notched wheel so that it may lock the shaft in any desired position of its movement.

In operation with this part of the structure,

and assuming that the side walls are in their extended positions, then in order to fold the floor sections 25 downwardly, the operator manually operates the shaft 28 in the direction required for permitting the cable to unwind from the pulley to permit the floor section to fold downwardly, and when it is desired to raise the floor section 25, the shaft 28 is operated in the opposite direction, and the floor section is then folded up against the frame member 26 and tension is applied to the cable before it is locked by the pawl, hence, when in this position the floor members are held under tension against the frame members, to avoid rattling.

For moving the side walls inwardly and outwardly I have provided a shaft 34 mounted in the foundation frame at about its longitudinal center, and having a pulley 35 fixed thereto. A cable 36 is fixed to an arm 37 at the lower portion of the side wall member and extended around the pulley 35, and its other end is fixed to an arm 38 on the end portion of the channel bar 19 of the opposite side wall. A similar cable arrangement is provided for the other side wall.

On the end of the shaft 34 is a notched wheel 39, and a pawl 40 is associated therewith. In operation, when the shaft 34 is rotated in one direction, and assuming that the parts are in the position shown in Figure 5, then the end of the cable attached to the arm 38 which is attached to the outer end of the long channel bar 20 will be moved toward the left and the left side wall will be moved to the left, and when the shaft 34 is turned in the opposite direction, the end of the cable that is attached to the adjacent arm 37 will be moved toward the right, as shown at the left lower portion of Figure 5, and by that means the side walls will be moved inwardly.

When the side walls are thus moved either inwardly or outwardly the cables attached thereto are brought under tension and the pawl 40 moved to locked position. Thereupon the side walls are held under tension either in their fully expanded or fully contracted positions, to avoid rattling.

There are two extension roof members, one on each side. These are indicated by the reference numeral 41 and are hingedly connected to the main roof member 14. This main roof member is preferably made of two spaced apart layers of sheet metal with insulating material between them. The upper sheet metal layer projects downwardly and outwardly at 42, as shown in Figure 4, and the hinge 43 is arranged below this extending roof member 42. The extension roof member has its upper layer of metal projected beyond the lower layer, and the position of the hinge is such that its lower roof member, when swung to the position shown in Figure 4, has its upper layer projecting under the extension 42 to form a water tight joint. This hinged roof member, however, may freely swing downwardly to the position shown in Figure 5.

For the purpose of automatically raising and lowering these roof members and holding them firmly in position when at either limit of movement, I have provided on each of the roof members 41 a channel 44, and on the adjacent corner of each of the end wall members 15 I have provided a roller 45 movable in said channel. By this means, when the end wall members are moved outwardly from the position shown in Figure 5, the rollers 45 operating in the channels 44 raise the roof member 41 to the position shown in Figure 4, and securely hold it in that position, then

when the end wall members 15 are moved inwardly, the roller operates in said channel bar in the manner required to fold the roof member into a downwardly extended position and there hold it securely against swinging movement.

In Figure 1 I have shown latches 46 which may be used to hold the lower edges of the roof member firmly against the adjacent side wall member when in its folded position, and in Figure 3 I have shown a door latch device 47 for securing together the two door sections 17 when the structure is in its fully collapsed position.

In practical use, and assuming that my improved structure is used as an automobile trailer, it may be of any suitable length, but not greater in width than that required by traffic regulations for trailers. When in this position the structure may be used as a trailer and all of the movable wall, floor and roof structural members are held under tension against each other to thereby avoid rattling and wear.

When it is desired to utilize the structure as a building it is only necessary for the operator to rotate the shaft 34 by hand, and the side walls, extension end walls and extension roof members will all simultaneously quickly and easily be moved to their extended position, and at the completion of this movement they are all of them automatically placed in substantially weather-tight condition and firmly held in said positions under tension. After the side walls have been extended, then the extension floor members may be quickly and easily lowered in position for use by turning the shaft 28.

When it is desired to again move the structure to its fully contracted position for trailer purposes or the like, the operator simply first manipulates the shaft to fold the floor sections upwardly, and then turns the other shaft in position for simultaneously moving the side walls inwardly, the extension end walls inwardly and the extension roof members downwardly, and the shaft is turned enough so that the cable is put under tension to hold said parts firmly together under tension to avoid rattling.

In the modification shown in Figures 9, 10 and 11 I have substituted for the single folding floor section 25 a floor formed of two sections 48 and 49 hinged together longitudinally, the outer edge of the section 48 being connected by hinges 50 with the adjacent side wall 18, and the inner edge of the floor section 49 being connected by hinges 51 with the main floor 24.

For operating these floor sections in unison with the expanding and contracting movements of the side walls I have provided a pulley 52 on the shaft 34, and to this pulley I have fixed a flexible cable 53 which extends horizontally outwardly and passes under a pulley 54 at the lower edge of the adjacent side wall, then upwardly a short distance and over a pulley 55 fixed to the adjacent side wall, then downwardly and inwardly and under a pulley 56 fixed to the central portion of the folding floor, and then upwardly and inwardly to a bracket 57 fixed to the stationary upright 22.

In order to make the folding floor weather proof and dust tight I form a series of alternate extensions 58 with recesses between them, place a hinge rod 59 below the floor and curve the said extension around the hinge rod with the ends of said extensions overlapping the top of the adjacent floor section. This also braces the floor between the floor supports 19. The floor sections are preferably made of thin sheet metal so that the overlapping extensions are not objectionable.

In practical operation with this form of floor, I have demonstrated that when the parts are in the position shown in Figure 11 and the pulley is turned in the direction of its top turning toward the right, then the cable 53 will pull upwardly upon the pulley 56 and fold the floor to the position shown by the dotted lines 59a. This folded floor is flat against the side wall 18 and extends upwardly only a short distance so that it does not interfere with the various articles of furniture, plumbing, cabinets or the like usually fixed to said walls above the floor. When the side wall is moved outwardly the hinges 50 and 51 serve to move the floor to horizontal position and the pulley 56 pulls the cable 53 downwardly at that point. It is to be understood that a similar pulley and cable structure is provided at each end of the trailer.

The pulley 52 is attached to the same shaft as the pulley 35 which aids in contracting and expanding the side walls, hence, the operator need turn only the one crank on the shaft 34 to contract and expand the entire structure, including the floor.

I claim as my invention:

1. In a building structure, the combination of a foundation frame, side walls, means for supporting the side walls in upright positions on the main frame and for permitting the side walls to move outwardly and inwardly, means for limiting the outward and inward movements of the side walls, a shaft carried by the foundation frame, a pulley on said shaft, two flexible cables each fixed at one end to one of the said walls, wound upon said pulley, a bar fixed to each side wall and extended transversely of the structure to a point adjacent the other side wall, said cables having their other ends attached to said bars, in such manner that a rotation of the pulley in one direction will move both side walls outwardly and a rotation of the pulley in the opposite direction will move both side walls inwardly.

2. In a building structure, the combination of a foundation frame, side walls, means for supporting the side walls in upright positions on the main frame and for permitting the side walls to move outwardly and inwardly, means for limiting the outward and inward movements of the side walls, a shaft carried by the foundation frame, a pulley on said shaft, two flexible cables each fixed at one end to one of the side walls, wound upon said pulley, a bar fixed to each side wall and extended transversely of the structure to a point adjacent the other side wall, said cables having their other ends attached to said bars, in such manner that a rotation of the pulley in one direction will move both side walls outwardly and a rotation of the pulley in the opposite direction will move both side walls inwardly, and means for locking the pulley against rotation when the cables have been placed under tension at either limit of their movement.

3. In a building structure, the combination of a foundation frame, side walls, means for supporting the side walls in upright positions on the main frame and for permitting the side walls to move outwardly and inwardly, means for limiting the outward and inward movements of the side walls, a shaft carried by the foundation frame, a pulley on said shaft, two flexible cables each fixed at one end to one of the side walls, wound upon said pulley, a bar fixed to each side wall and extended transversely of the structure to a point adjacent the other side wall, said cables having their other ends attached to said bars, in

- such manner that a rotation of the pulley in one direction will move both side walls outwardly and a rotation of the pulley in the opposite direction will move both side walls inwardly, and means for locking the pulley against rotation when the cables have been placed under tension at either limit of their movement, said means comprising a notched disc fixed to the shaft and a pawl carried by the foundation frame.
10. 4. In a building structure, the combination of a foundation frame, side walls, means for supporting the side walls in upright positions on the main frame and for permitting the side walls to move outwardly and inwardly, a main floor section carried by the foundation frame, a side floor section hinged to each side edge of the main floor section, means for limiting the movement of the side floor sections when they assume approximately upright positions, and means for simultaneously swinging said side floor sections from horizontal to upright positions and back, comprising a shaft carried by the foundation frame, a pulley on the shaft, a cable for each side floor section fixed at one end to the outer edge of the side floor section and fixed to and wound upon the pulley, and an elevated pulley for guiding the end portion of the cable which is attached to the side floor section.
5. In a structure of the class described, the combination of a frame, a main roof section fixed to the frame, an extension roof section hinged to the main roof section, a side wall supported by the frame for movement outwardly and inwardly relative to the frame, and means applied to the side wall and extension roof section for automatically raising the extension roof section as the side wall moves outwardly and lowering it as the side wall moves inwardly, and for holding the extension roof section against swinging movements on its hinge when in any position of its movement.
6. In a structure of the class described, the combination of a frame, a main roof section fixed to the frame, an extension roof section hinged to the main roof section, a side wall supported by the frame for movement outwardly and inwardly relative to the frame, a grooved track carried by the extension roof section, and a roller carried by the side wall and fitted into the groove for the purposes stated.
7. In a building structure of the class described,
- the combination of a frame, an end wall fixed to the frame, two extension end wall members slidably mounted adjacent the outer surface of said end wall, means for jointly moving them toward and from each other, and means for limiting their movements in both directions, said end wall being formed with a centrally arranged door opening and said extension wall sections each having a hinged door at its inner edge and grooved guides fixed to the frame to receive the lower edges of the extension wall sections to hold the hinged portions thereof in line when the extension wall sections are at their outer limit of movement.
8. The combination with a building structure having a fixed frame, a fixed floor thereon, and a side wall movable outwardly and inwardly relative to the fixed frame, of a folding floor structure comprising two longitudinally arranged floor sections hinged together at their adjacent edges and one hinged to a part of the fixed frame and the other hinged to a part of the movable side wall, means for raising the hinged together edges of the floor sections and for moving the side wall inwardly, said means comprising a shaft, a pulley and cable structure operated by the shaft for moving the side wall inwardly and outwardly and a pulley and cable structure operated by the same shaft for elevating the hinged together edges of the floor sections during the inward movement of the side wall.
9. In a device of the class described, the combination of a fixed frame member, a side wall movable outwardly and inwardly relative to the fixed frame member, two floor sections hinged together at their adjacent edges, one of them hinged at its inner edge to the fixed frame member and the other hinged at the outer edge to the movable side walls, a cable attached at one end to a part of the fixed frame member, extended downwardly and toward the hinged together edges of the floor sections, a pulley carried by the floor sections adjacent their hinged together edges, said cable being passed under said pulley, a pulley carried by the movable side wall, said cable being extended upwardly and outwardly and being passed around the upper side of said pulley, and means for applying power to said cable in the direction for raising the hinged together edges of the floor sections.

ARCHIE B. GRAY. 50
